UNITED STATES PATENT OFFICE

2,233,536

EXTENSION ARM ATTACHMENT FOR JACKS

Burton J. Kelley, Punxsutawney, Pa.

Application April 9, 1940, Serial No. 328,747

4 Claims. (Cl. 254—134)

This invention relates to improvements for attachments for jacks and particularly to an extension lifting arm for the same.

It is an object of this invention to provide a novel lifting arm extension useful in conjunction with existing types of jacks which may with facility be attached to or disconnected from the jack without requiring the use of special tools or the like.

Another object of this invention is to provide a lateral extension arm assembly attachable to existing types of jacks whereby when the jack is used to raise an automobile or the like the head of the jack plunger can be engaged with a portion of the chassis and the extension arm engaged with a part of the axle whereby both axle and chassis can be simultaneously lifted.

Another object of this invention is to provide a mechanical assembly attachable to each of the several existing types of jacks which will include a vertically attachably swingable lifting arm permitting the intended use of the jack with any type of vehicle irrespective of the relative position of parts of the chassis against which the lifting head of the jack is used and the axle under parts.

As must follow from what has been said above, an important advantage of the novel jack extension lifting arm according to this invention is that it permits simultaneous lifting of a vehicle chassis and axle with the result that it is not now necessary as heretofore to raise the vehicle chassis until the vehicle spring has passed its maximum downward extension and raised the vehicle.

Noteworthy among the features of the novel jack according to the present invention are its simplicity and ruggedness of construction, the former suiting the device to the requirements of manufacture under conditions of mass production and the latter assuring long useful life.

Other objects, advantages and features of the new and improved jack according to the present invention will be apparent to those skilled in this art during the course of the following description.

Regarded in certain of its broader aspects the present invention comprises in combination with a jack of the type having a vertically reciprocable plunger, the improvements which comprise an outwardly extending swinging arm connected to and movable with said plunger for supporting at other points objects resting upon said plunger.

In order to facilitate a fuller and more com-

plete understanding of the present invention a specific embodiment thereof herein illustrated will be hereinafter described, it being clearly understood, however, that the illustrated embodiment, although presently preferred, is provided solely by way of example of the practice of this invention and not by way of limitation thereof except insofar as the invention is recited in the subjoined claims.

Referring then to the drawing.

Figure 1 is substantially a side elevational view of the presently preferred embodiment of this invention illustrating use of the same in the lifting of a conventional automotive vehicle.

Fig. 2 is essentially an enlarged side elevational view of the device shown in Fig. 1 showing details of the structure thereof.

Fig. 3 is essentially a horizontal sectional view of Fig. 2, taken along the line 3—3.

Fig. 4 is a perspective view of the supporting member forming a part of the device of the present invention.

Fig. 5 is a detail view partially in section of portions of the extension arm.

Fig. 6 is a side elevational view in modified form of the novel device according to this invention, and

Fig. 7 illustrates in side elevational view the application of the extension arm according to this invention to another type of jack.

Referring now particularly to Figs. 2 to 5 inclusive of the drawing wherein the presently preferred embodiment of this invention is illustrated, it will be noted that the device generally designated by the reference character 10 comprises a bar-like member 11 substantially T-shaped in cross sectional outline and receivable within a vertically extending T-shaped slot formed in a side of the jack generally designated by the reference character A. A horizontally extending top piece 12 integrally formed with the member 11 is downturned on its extreme end 13 to facilitate engagement with the head B of the jack whereby the member and the jack plunger can be moved simultaneously.

An outwardly projecting bracket 14 mounted on the member 11 near the base of the jack is provided with openings to receive a pivot 15 carrying an extension arm generally designated by the reference character 16 whereby free swinging motion of the arm within a vertical plane is permitted.

The arm 16 is longitudinally adjustably extensible and comprises an arm proper 17 which is connected at one end to the bracket 14 above described and which carries a longitudinally 50 described and which carries a longitudinally 55

extending rib or tongue 17a receivable in a groove formed in an extension 18 which is coupled to the arm 17 by means including a band 19 circumjacent parts of said arm and said extension essentially as shown.

A pin 20 removably mounted in the band 19 is engageable with openings 18a in the extension 18, thus facilitating the holding of the extension with respect to the arm in a selected adjustment.

10 The distal free end of the extension arm 18 is upturned to provide a hook element 18b for engaging with parts of the object to be lifted as will hereinafter be described.

A chain 21 connected to an eye 22 attached 15 to the band 19 can be engaged with a hook 23 mounted upon the member 11 near the top thereof whereby the extension arm can be held at a selected angularity with respect to the essentially upright member 11 as will be apparent from an 20 inspection of the drawing.

In the embodiment of the invention illustrated in Fig. 6 a lifting extension arm generally designated by the reference character 30 is shown mounted upon a jack generally designated by the 25 reference character D. A hook 31 attached to the jack plunger E near the top thereof corresponds to the hook 23 in the first described embodiment of this invention and engages with a chain 32 connected to a collar 33 upon a longitudinally extensible arm 34 swingably mounted 30 in a bracket 35 attached to a side part of the jack. The arm includes an integrally formed hook element 34a which is engageable with parts of the object to be lifted as will be hereinafter described.

35 A third embodiment of this invention is illustrated in Fig. 7 wherein a jack F is shown equipped with an adjustable lifting arm extension generally designated by the reference character 40 comprising a downwardly extending member 41 integrally formed with a portion of the jack shoe 42 carried on the jack plunger 43. A bracket 44 mounted on the member 41 serves swingably to hold a longitudinally adjustable extension arm generally designated by the reference character 45 and comprising interconnected elements 46 and 47 similar to the swinging arm 17 and extension 18 described in connection with the first illustrated embodiment of this invention. A lifting arm is held in a selected angularity with respect to the member 41 by means of a chain 48 attached to a band 49 mounted on the arm and to a hook 50 mounted upon the member near the top thereof. A hook formation 48a is 50 provided upon the end of the extension arm to facilitate gripping of parts of the object to be lifted as subsequently will be described. A guide bolt 51 mounted in a bottom portion of the member 41 projects into a vertically extending slot 55 formed in the side of the jack, thereby assuring smooth vertical movement of the member during use.

Each of the described embodiments of this invention is used in substantially the same manner and, accordingly, a description of the mode of use of the embodiment illustrated in Figs. 1 to 5 inclusive will suffice for and be applicable to each of the embodiments of this invention.

Assuming it is desirable to lift a portion of the 70 vehicle, as for instance it is necessary in replacing a wheel or a tire, the shoe portion B of the jack A is positioned beneath a part of the vehicle chassis, such for instance as the bumper X in Fig. 1, and the hook element 18b of the extension 75 arm 18 is positioned beneath a part of the vehicle

axle Y, appropriate adjustment of the chain 21 upon the hook 23 being made to assure simultaneous lifting of the axle and the bumper. The jack is then operated to cause the plunger thereof to rise and, as will be apparent from what has been said above, the member 11 will be carried with the plunger, thereby also carrying the extension arm 18 engaging with the vehicle axle. In this manner the axle is moved simultaneously with the bumper and sagging of the vehicle 10 spring Z is precluded.

It is to be understood that this invention is capable of extended application and is not confined to the precise illustrated forms nor described construction and, therefore, such changes 15 and modifications may be made therein as do not affect the spirit of the invention nor exceed the scope of the appended claims.

Having thus described the present invention, what it is desired to secure in Letters Patent is: 20

1. In combination with a jack of the type including a vertically movable support, the improvement which comprises a vertically extending member mounted on and movable with said support; an arm, swingable in a vertical plane, 25 mounted on said member near the base of the jack; a hook element on the free distal end of said arm; and a coupling of adjustable length connecting the top end of said member with said arm.

2. In combination with a jack of the type having a vertically reciprocable plunger, the improvements which comprise a downwardly extending member connected at its top to the top end of said plunger; a bracket mounted on said member near the bottom thereof; an arm swingably mounted in said bracket, means for longitudinally extending said arm comprising a bar-like element grooved to be slidably received upon the distal part of said arm, and means for rigidly connecting said arm and said element together; an upturned hook element on the end of said arm distal with respect to the bracket; and means for holding said arm in a selected angular relationship with respect to said member comprising a collar mounted on said arm between the bracket and the hook element, a hook on said member near the top thereof, and a chain connected at one end to said collar engageable with said hook.

3. In combination with a jack of the type including a vertically movable support, the improvement which comprises a vertically extending member mounted on and movable with said support; a longitudinally adjustably extensible arm, swingable in a vertical plane, mounted on said member near the base of the jack; an upturned hook element formed on the free distal end of said arm; and a coupling of adjustable length connecting the top end of said member with said arm at a place near the midpoint thereof.

4. In combination with a jack of the type having a vertically reciprocable plunger, the improvements which comprise a downwardly extending member connected at its top to the top end of said plunger by means including a horizontally extending hook element integrally formed on said member adapted to overlie and engage with parts of the plunger top; a bracket 70 mounted on said member near the bottom thereof; an arm swingably mounted in said bracket, means for longitudinally extending said arm comprising a bar-like element grooved to be slidably received upon the distal part of said arm 75

and means for rigidly connecting said arm and said element together; an upwardly opening hook element on the end of said arm distal with respect to the bracket; and means for holding said arm in a selected angular relationship with respect to said member comprising a collar mount-

ed on said arm between the bracket and the hook element, a hook on said member near the top thereof, and a chain connected at one end to said collar engageable with said hook.
